UNITED STATES PATENT OFFICE.

CHARLES F. PYM, OF LYNN, MASSACHUSETTS, ASSIGNOR TO UNITED SHOE MACHINE CORPORATION, OF PATERSON, NEW JERSEY, A CORPORATION OF NEW JERSEY.

GRIPPER.

Original application filed August 15, 1917, Serial No. 186,314. Divided and this application filed July 25, 1922. Serial No. 577,377.

To all whom it may concern:

Be it known that I, CHARLES F. PYM, a subject of the King of England, residing at Lynn, in the county of Essex and State of Massachusetts, have invented certain Improvements in Grippers, of which the following description, in connection with the accompanying drawings, is a specification, like reference characters on the drawings indicating like parts in the several figures.

This invention relates to grippers for use in machines for pulling uppers over lasts, the present application being a division of my earlier application Serial No. 186,314 filed on August 15, 1917, upon which Letters Patent No. 1,436,194 were granted on Nov. 21, 1922.

An object of the invention is to provide an improved gripper adapted for use to pull the toes of uppers. Features of the invention are to be recognized in a novel construction affording provision for relative adjustment of different pairs of gripper jaws to conform to different shapes of toes, a novel arrangement affording an equalizing connection between different pairs of gripper jaws which are relatively movable to conform to different shapes, whereby the different pairs of jaws in any position which they assume are closed with substantially equal pressures, and a novel combination of gripper tripping means with pairs of jaws that are relatively movable as above set forth.

The above and other features of the invention, including certain details of construction and combinations of parts, will now be more particularly described by reference to the accompanying drawings and pointed out in the claims.

In the drawings,

Fig. 1 is a view in side elevation of the novel toe gripper and associated parts of the machine shown in my prior application, and

Fig. 2 is a perspective view of the gripper with portions of the structure broken away to show parts that lie beneath.

The gripper herein shown, in common with grippers in use heretofore in machines of the well known type illustrated in my prior application, comprises a bar 2 connected at its upper end to an updraw lever 4 which is operated and controlled in the

usual manner, the bar 2 at its lower end being slidably movable in a gripper casing 6 which has on its opposite sides lugs 8 for engagement with the frame of the machine to limit downward movement of the casing in the return of the parts to starting position after the upper has been pulled. It will be understood that when the lugs 8 engage the frame the bar 2 continues its downward movement against the resistance of a spring 10 which is positioned in a recess in the bar and acts oppositely against the bar and a block 12 secured within the casing. The bar 2 is provided in its lower end with a slot to embrace the block 12 and permit the bar to extend downwardly below the block.

The gripper is provided with two pairs of jaws, each comprising a fixed jaw 14 and a pivoted jaw 16, and each pair of jaws is mounted on a holder 18 which has a cylindrical extension 20 mounted to turn in the casing 6 to adjust the jaws to different shapes of toes. In the construction shown each holder 18 may be adjusted independently of the other and is secured in adjusted position by a set screw 22 which is threaded in the casing 6 and engages the extension 20.

Each of the pivoted jaws 16 is provided with a curved shank portion engaged by a roll 24 on a jaw closing member 26, the latter comprising a stem having a bearing in the extension 20 and movable lengthwise of said extension. Each of the cylindrical extensions 20 is provided with a peripheral slot to expose a portion of the closing member 26, and in the location of said slot each closing member is provided with a peripheral groove 28 to receive an end of an equalizer bar 30 through which the members 26 are operated to close the jaws and to pull the upper. The equalizer 30 is pivoted at 32 on a block 34 slidably mounted in the casing 6, and by reason of its freedom to rock about its axis it permits relative movements of the different closing members 26 in such manner as substantially to equalize the pressures under which the upper is gripped by the different pairs of jaws. It will be understood that the slots in the cylindrical extensions 20 are of sufficient dimensions to permit the equalizer to maintain its operative connection with the dif-

ferent closing members in all positions of adjustment of the different pairs of jaws and also to permit movements of the equalizer and the closing members lengthwise of 5 the extensions as far as may be required for closing the jaws upon different uppers.

For imparting jaw closing and pulling movement to the equalizer 30 the gripper bar 2 carries a latch 36 which is pivoted on 10 the bar and is swung by a spring 38 into position to hook under a ledge on the block 34. It will be understood that in the upward movement of the bar 2 the spring 10 first acts to hold the casing 6 in its lowermost position, to render the bar effective to 15 impart through the equalizer 30 such movements to the closing members 26 as to close the jaws firmly upon the upper, and that by further movement of the bar the casing 6 is 20 lifted with the jaws to pull the upper.

At a predetermined time in the cycle of the machine, after the pulling of the upper, the gripper is "tripped" to cause it to release the upper by disconnecting the latch 36 from the block 34. Different means may be employed within the scope of the present invention for thus operating the latch to break the connection between the gripper bar and the jaws, the construction shown comprising 30 mechanism described in detail in my prior application. Generally speaking, this mechanism comprises a member 40 which is pivoted on the block 34 and is arranged to force the latch 36 rearwardly to trip or release the block, the member 40 being connected by 35 a link 42 to an arm 44 which is pivoted on the bar 2 and is engaged by a member 46 on the wiper carrying arm 48 of the machine. It will be understood that the downward 40 movement of the bar 2 relatively to the casing 6 in the return of the parts to starting position serves to carry the latch 36 into position to connect the bar again to the block 34 ready for the operation of the gripper 45 upon the next shoe.

Having described the invention, what I claim as new and desire to secure by Letters Patent of the United States is:

1. A toe gripper having, in combination, a 50 plurality of pairs of gripper jaws mounted for relative movements to conform to different shapes of toes, and means for closing said jaws upon an upper in any position of the jaws comprising a member arranged to be tripped after the upper has been pulled to cause the different pairs of jaws to release the upper.

2. A toe gripper having, in combination, a 60 plurality of pairs of gripper jaws mounted for relative turning movements to conform to different shapes of toes, a member having operative connection with the different pairs of jaws in all positions which they assume in conformity to different shapes, and means 65 for imparting jaw closing and pulling move-

ment to said member comprising a latch movable after the upper has been pulled to release said member and permit the opening of the jaws.

3. A toe gripper having, in combination, a 70 gripper casing, a plurality of pairs of gripper jaws carried by said casing and relatively movable to conform to different shapes of toes, a gripper bar, and means comprising a latch for connecting said gripper bar 75 to the jaws in any position of the jaws to close them and to operate them to pull an upper, said latch being movable after the upper has been pulled to disconnect the bar from the jaws to cause the jaws to release 80 the upper.

4. A toe gripper having, in combination, a gripper casing, a plurality of pairs of gripper jaws carried by said casing and mounted for relative turning movements to 85 conform to different shapes of toes, a closing member for each pair of jaws, an intermediate member connected to the different closing members in all positions which the different pairs of jaws assume in conformity 90 to different shapes of toes, a gripper bar, a latch connecting said gripper bar to said intermediate member for imparting closing and pulling movements to the jaws, and means for operating said latch after the upper has been pulled to release said intermediate member and permit the jaws to open. 95

5. A toe gripper having, in combination, a gripper casing, a plurality of pairs of gripper jaws carried by said casing, each of said 100 pairs of jaws being mounted for turning movement in said casing to adjust the gripper to different shapes of toes, and means for securing the different pairs of jaws in adjusted position.

6. A toe gripper having, in combination, a gripper casing, a plurality of pairs of gripper jaws carried by said casing, a holder for each pair of jaws having a cylindrical portion extending within said casing to permit turning of the holder to adjust the jaws for different shapes of toes, and means for securing each holder in adjusted position in the casing. 110

7. A toe gripper having, in combination, 115 a gripper casing, a plurality of pairs of gripper jaws carried by said casing, each of said pairs of jaws being adjustable independently of the other pair to conform to different shapes of toes, means for securing the jaws in adjusted position, and jaw closing mechanism arranged to maintain an operative connection with the different pairs of jaws in all positions of their adjustment. 120

8. A toe gripper having, in combination, a 125 gripper casing, a plurality of pairs of gripper jaws carried by said casing, a holder for each pair of jaws having a cylindrical extension mounted in said casing for turning movement to adjust the jaws for different 130

- shapes of toes, means for securing said holders in adjusted position, a closing member for each pair of jaws movable lengthwise of said cylindrical extension and having 5 a peripheral groove therein, an intermediate member extending into the grooves in said closing members to maintain an operative connection with said members in all positions of adjustment of the jaws, and means 10 for imparting jaw closing and pulling movement to said intermediate member comprising a latch movable after the upper has been pulled to release said member and permit the opening of the jaws.
- 15 9. A toe gripper having, in combination, a plurality of pairs of gripper jaws mounted for relative movements to conform to different shapes of toes, and means for closing said jaws on an upper comprising an 20 equalizing connection between the different pairs of jaws for substantially equalizing the pressures under which the upper is gripped by the different pairs in any position of the jaws.
- 25 10. A toe gripper having, in combination, a plurality of pairs of gripper jaws mounted for relative turning movements to conform to different shapes of toes, a closing member for each pair of jaws, an equalizer having 30 operative connection with said closing members in all positions which the different pairs of jaws assume in adjustment to different shapes of toes, and means for imparting through said equalizer jaw closing movements to said closing members, said equalizer being movable in the closing of the jaws to equalize substantially the pressures under 35 which the upper is gripped by the different pairs of jaws.
- 40 11. A toe gripper having, in combination, a gripper casing, a plurality of pairs of gripper jaws carried by said casing, a holder for each pair of jaws having a cylindrical portion extending within said casing to permit 45 turning movement of the jaws to con-
- form to different shapes of toes, a closing member for each pair of jaws movable lengthwise of said cylindrical extension and having a peripheral groove therein, and means for imparting jaw closing movement 50 to said closing members comprising an equalizer extending into said grooves and movable to effect a substantial equalization of the pressures under which the upper is gripped by the different pairs of jaws. 55
12. A toe gripper having, in combination, a plurality of pairs of jaws mounted for relative turning movements to conform to different shapes of toes, closing members for the different respective pairs of jaws, an equalizer connected to said closing members and movable to effect substantial equalization of the pressures under which the upper is gripped by the different pairs of jaws 60 while maintaining its operative relation to said different pairs in any positions to which they are turned, and means for imparting jaw closing and pulling movement to said equalizer comprising a latch movable after the upper has been pulled to release said 65 equalizer and permit the opening of the jaws.
13. A toe gripper having, in combination, a gripper casing, a plurality of pairs of gripper jaws carried by said casing and 70 relatively adjustable to conform to different shapes of toes, an equalizer connected to the different pairs of jaws in all positions of their adjustment for substantially equalizing the closing pressures of the different pairs of jaws upon the upper, a gripper bar, a latch connecting said gripper bar to the equalizer for closing the jaws and for operating them to pull the upper, and means for moving said latch after the upper has 75 been pulled to release said equalizer and permit the opening of the jaws.
- In testimony whereof I have signed my name to this specification.

CHARLES F. PYM.
